Patented Jan. 9, 1973

225,876

WHIRLING TOY BALL OR THE LIKE

William Vath, Massapequa, N.Y., assignor to Long Island Mold and Tool Corp., Westbury, N.Y.

Filed Mar. 31, 1971, Ser. No. 130,068

Term of patent 14 years

Int. Cl. D21—01
U.S. Cl. D34—15

FIG. 1

FIG. 2

FIG. 4

FIG. 3

FIG. 1 is a top view of a whirling toy ball showing my new design.

FIG. 2 is a side view of the device shown in FIG. 1;

FIG. 3 is a bottom view of the device shown in FIG. 1; and

FIG. 4 is a cross-section taken along lines 4—4 in FIG. 1.

I claim:

The ornamental design for a whirling toy ball or the like, as shown and described.
